UNITED STATES PATENT OFFICE.

EDWARD O. PARTRIDGE, OF CHICAGO, ILLINOIS.

GRINDING-MACHINE.

1,078,551.

Specification of Letters Patent. Patented Nov. 11, 1913.

Application filed January 17, 1913. Serial No. 742,565.

To all whom it may concern:

Be it known that I, EDWARD O. PARTRIDGE, citizen of the United States, residing at Chicago, in the county of Cook and State 5 of Illinois, have invented certain new and useful Improvements in Grinding-Machines; and I do hereby declare the following to be a full, clear, and exact description of the invention, such as will enable others 10 skilled in the art to which it appertains to make and use the same.

My invention relates to grinding machines and particularly to machines employing abrasive wheels made of emery or carborundum. Its objects are to provide a 15 safety guard or hood which will be readily adjustable in position to conform to variations in the diameter and thickness of the wheel, and in the spacing of the latter longitudinally of the shaft upon which it is mounted; in which the safety hood or shield may be securely clamped in any desired position, and in which auxiliary supports will 20 add to the firmness and the safety afforded by the protecting hood or shield. I accomplish these objects by the construction shown in the accompanying drawings, in which:

Figure —1— is a fragmentary side elevation of a grinder embodying my invention. Fig. —2— is a fragmentary front elevation of the same. Fig. —3— is a view similar to Fig. —1— but with the guard-hood adjusted to protect a smaller wheel. Fig. —4— is an enlarged fragmentary rear view, partly in section, of the grinder of Fig. —1—. Fig. —5— is an enlarged fragmentary section through Fig. —1— along the line 5—5, with the hood shifted laterally 40 of its supports. Figs. —6— and —9— are side elevations of alternative embodiments of my invention. Fig. —7— is a vertical section through Fig. —6— along the line 7—7. Fig. —8— is an enlarged fragmentary rear view of the embodiment shown in Fig. —6—. Fig. —10— is an enlarged rear elevation of a portion of the grinder shown in Fig. —9—. Fig. —11— is a fragmentary section through an alternative form of hood 45 and auxiliary support.

In the drawings, the abrasive wheel 1 is mounted upon a shaft 2, being laterally clamped between washers 3 and a collet 4 by a nut 5 engaging the threaded end of 55 the shaft. The shaft 2 is mounted on a bearing 6 forming part of a support, this support

consisting preferably of a column 7 having a horizontal table 8 positioned beneath the wheel. The shaft 2 is prevented from moving longitudinally of the bearing 6 by the 60 collet 4 and by the hub 9 of the driving pulley 10, which latter is secured to the shaft at the opposite side of the bearing from the abrasive wheel.

The table 8 is provided at one edge with 65 trunnions 11, to which links 12 and 13 are pivotally connected by bolts 14 and 15, these links being pivotally connected at their other ends by bolts 16 and 17 to an inflexible guard-hood 18 adapted to partly house the 70 upper portion of the grinding wheel 1. The safety shield or hood 18 is preferably made of two symmetrical parts, formed of sheet steel, each of the said parts having a flange portion 19 adapted to depend at one side of the 75 wheel, and a web portion 20 projecting outwardly of the hood proper. When the hood is thus made of two parts, the latter are secured to each other by rivets 21 passing through the adjoined webs 20, which latter 80 then constitute an outer stiffening rib for the hood. This stiffening rib also has a plurality of perforations 22 adapted interchangeably to fit a transverse bolt 23 connecting the eye ends of eye-bolts 24 and 25 85 which project through slots 26 in the table 8 of the supporting structure of the grinder and each of which bolts is secured to the said table by nuts 31. When the bolts 23, 24 and 25 are thus assembled, they constitute a substantially vertical link formation 90 which acts as a rigid auxiliary support or brace for the guard-hood. When the grinding wheel is decreased in size, either by substituting one of smaller diameter or by 95 the gradual wear upon the periphery of the wheel, the hood may be kept in a proper guarding position by tilting it downwardly upon the links 12 and 13, the vertical brace link being correspondingly adjusted by 100 moving the nuts 26 upon the bolts 24 and 25. Instead of having the rear ends 27 and 28 of the hood supported by links laterally spaced to correspond to the spacing between these links 12 and 13, I preferably space 105 these links farther apart than the outer edges of the said rear ends, thereby providing room for washers 29 upon the bolt 16, as shown in Fig. —4—. By transferring some of these washers from one side to the 110 other, as in Fig. —5—, the hood may be moved laterally of its supports (or longitudu-

dinally of the shaft of the grinder), thereby permitting it to be centered over the wheel with wheels of varying thicknesses, or with various thicknesses of washers 3 and guard-disks 30. To allow for such a lateral motion of the hood, the perforations 26 in the table 8 are elongated into slots extending parallel to the shaft 2.

While the guard of my invention may be connected to the support by a single link or pair of links, as in Figs. —6—, —8—, —9— and —10—, I preferably use two pairs of links connected at their opposite ends, respectively, to vertically separated parts of the hood and of the support. I also preferably provide one pair of these links with slots 32, thereby permitting the hood to be adjusted through a wider range of positions than would be feasible without this slotting. By this added adjustment I am enabled to expose varying portions of wheels of the same diameter, as shown by full and dotted lines in Fig. —3—, thereby permitting of different classes of grinding while still effectively shielding the wheels. When the guard-hood or shield is thus supported by two pairs of links, as in Figs. —1— and —3—, the substantially vertical auxiliary brace may be omitted if desired, although I still prefer to employ the same as giving the hood increased stability in case pieces of the abrasive wheel should be thrown centrifugally against the hood by the breaking of the wheel.

Instead of passing the horizontal portion 23 of the auxiliary link through perforations 22 in the rib upon the hood, this rib may be provided with notched formations 36 adapted interchangeably to engage the link portion 23, as in Figs. —9— and —11—. The latter shows a construction in which the horizontal portion 23 of the auxiliary link engages notches in the cast rib 33 upon the hood, while the portions 24 and 25 have shoulder formations 34 adapted vertically to engage lateral flanges 35 upon the hood. Instead of making the hood of two adjoined sheet metal parts, it may be made of a single integral casting 37, as in Figs. —9—, —10— and —11—. So also, the links supporting the hood at its rear end may be united into a single cast link 38 and the latter may be pivoted to the support below the table, as in Figs. —9— and —10—. In view of these and of other modifications which may be made without departing from the spirit of my invention, I do not wish to be limited to the details of construction or arrangement as herein disclosed, but claim as new:

1. In a grinder, a shaft; an abrasive wheel mounted thereon; a support for the shaft; a guard-hood adapted to partially cover the wheel; and link members connecting the guard-hood with the said support, one of

the said link members being adjustable as to its point of engagement with the guard-hood, and also adjustable as to the distance between its points of engagement with both the guard-hood and the said support. 70

2. In a grinder, a shaft; an abrasive wheel mounted thereon; a support for the shaft; an inflexible guard-hood adapted to partially cover the wheel; and link members connecting the guard-hood with the said support, one of the said link members being adjustable as to its point of engagement with the guard-hood. 75

3. In a grinder, a shaft; an abrasive wheel mounted thereon; an inflexible guard-hood adapted to partially cover the wheel, and a pair of substantially parallel links pivotally connecting one end of the guard-hood with the said support, the said links being joined to the guard-hood at vertically separated points. 80

4. In a grinder, a shaft; an abrasive wheel mounted thereon; a support for the shaft; a guard-hood adapted to partially cover the periphery and sides of the wheel, and a plurality of links pivotally connecting one end of the guard-hood with the said support; the said links being disposed substantially vertically of each other, and being adjustable with respect to the said support transversely of the hood. 90

5. In a grinder, a shaft; an abrasive wheel mounted thereon; a support for the shaft; a guard-hood adapted to partially house the periphery and sides of the wheel; and a link supporting the guard-hood, the said link being pivotally connected at its opposite ends to one end of the guard-hood and to the support respectively; the guard-hood being adjustable with respect to the said link in a direction parallel to the said shaft. 100

6. In a grinder, a shaft; an abrasive wheel mounted thereon; a support for the shaft; a guard-hood adapted to partially house the periphery and sides of the wheel; and a link pivotally connecting an end portion of the guard-hood with the said support; both ends of the said guard-hood being movable transversely of the shaft; and a brace connecting another portion of the guard-hood with the support, there being coacting formations upon the guard-hood for interchangeably engaging the said brace. 110

7. In a grinder, a shaft; an abrasive wheel mounted thereon; a support for the shaft; an inflexible guard-hood pivotally mounted at one of its ends upon the said support and adapted partially to cover the said wheel, there being a stiffening rib upon the said guard-hood; and a brace connecting the said guard-hood with the said support, there being coacting formations upon the said stiffening rib for interchangeably engaging the said brace. 120

8. In a grinder, a shaft; an abrasive wheel 130

mounted thereon; a support for the shaft; an inflexible guard-hood pivotally mounted at one of its ends upon the said support and adapted partially to cover the said wheel, 5 the said guard-hood comprising a pair of laterally adjoined members having contacting web portions extending outwardly of the hood; fastening means for securing the said web portions to each other; and a brace

connecting the said laterally adjoined hood members with the said support.

In testimony whereof I have signed my name in presence of two subscribing witnesses.

EDWARD O. PARTRIDGE.
